Decker

UNITED STATES PATENT OFFICE.

MATTINE F. DECKER, OF MINNEAPOLIS, MINNESOTA.

SMOOTHING IRON.

Application filed April 20, 1923. Serial No. 633,545.

To all whom it may concern:

Be it known that I, MATTINE F. DECKER, a citizen of the United States, residing at Minneapolis, in the county of Hennepin and 5 State of Minnesota, have invented certain new and useful Improvements in Smoothing Irons, of which the following is a specification.

This invention relates to devices for 10 smoothing, creasing and pressing garments, and the main object is to provide an electrically heated body member particularly adapted for use by tailors and seamstresses, to be used by them when making garments, 15 for creasing and pressing small parts or portions of the same. Further objects will be disclosed in the course of the following specification, and are embodied in the structure illustrated in the accompanying drawing, 20 wherein:

Fig. 1 shows a base portion or cabinet of a portable type of small sewing machine, in which is embodied my invention.

Fig. 2 is a view similar to Fig. 1, but 25 showing the cabinet door open and my improved pressing device swung out into operative position.

Fig. 3 is a horizontal section, as seen substantially on the line 3—3 in Fig. 2.

Fig. 4 is an enlarged sectional elevation on the line 4—4 in Fig. 2.

Referring to the drawing more particularly and by reference characters, 5 designates a well known and common construction of sewing machine cabinet, having a downwardly swinging door 6, hinged as at 7.

On a fixed pin 8, within the cabinet 5, is journaled the angular integral extension 9 of a base or shelf 10. The door 6 may be provided with a snap spring 11 to releasably hold the shelf 10 in an extended position, as shown in Figs. 2 and 3.

A semi-cylindrical hollow body member 12 is provided with integral legs 13, which are secured to the shelf 10. The member 12 is closed at one end by a cap 14, and within the member is housed an electrical heating element 15, having a pair of terminals 16, projecting through the cap 14 to be connected to a socket 17 of a circuit cable 18. The bottom of the member 12 is insulated from the heating element, as at 19, so that the major portion of the heat will be absorbed by the upper part of the member, which upper part is suitably curved, as shown in Fig. 4.

A thin sheet metal casing 20 may be used to secure the heating element and insulation together, so that they may be inserted or removed as a unit. 60

The operation and use of the device may be briefly described as follows:

A garment maker in sewing a garment is frequently required to press out seams and even out small parts of the garment, while 65 sewing the various pieces together. Heretofore it has therefore been customary for him, or her, to frequently get up and go to an ironing board or table and press the parts down with an ordinary flat iron. 70 This, in the present instance, is unnecessary. After the door is opened the iron is pulled out and connected with an electric circuit, until it becomes properly heated. Now, when, for instance a seam is to be pressed 75 out, the operator takes hold at each end thereof with his hands, and slides the seam over the iron, whose upper surface is very smooth. The garment may be slightly moistened if so desired. By briskly pulling 80 the seam over the iron a number of times the desired result is readily accomplished, and the operator may then continue with the sewing operation, with but very little delay.

It is understood that the device need not 85 necessarily be mounted but may be complete as a unit which can be placed on a table or other support. It is further understood that suitable modifications may be made in the general design and structural details of 90 the device as herein shown, provided, however, that such modifications come within the spirit and scope of the appended claims. Having now therefore fully shown and described my invention, what I claim to be 95 new and desire to protect by Letters Patent is:

1. In a device of the class described, a main body member having a curved smooth top surface for smoothing and creasing purposes and an electric heating element, within 100 the member, to heat said surface.

2. In a device of the class described, a hollow body member having a curved upper surface for smoothing and creasing purposes, and a heating element located within 105 the member, to heat said surface.

3. In a device of the class described, a hollow body member having a curved upper surface for smoothing and creasing purposes, a heating element in the member to 110 heat the upper portion thereof, and an insulation between the bottom of the element

and the body member, to prevent overheating of the lower end of the body member.

4. In a device of the class described, a hollow body member having a curved upper surface for smoothing and creasing purpose, a heating element located within the member to heat the same, and terminals of said heating element extending from one end of the body member.

10 5. In combination in a cabinet of the character described having a door, a base pivotally mounted in the cabinet to swing out when the door is open, a body member, having a curved upper surface for smooth-

ing and creasing purposes, on the base, and 15 means for heating the said body member.

6. In combination in a cabinet of the character described, a base pivotally mounted in the cabinet to swing out therefrom, a body member having a curved upper surface for smoothing and creasing purposes, 20 on the base, means for heating the said body member, and means for releasably holding the base in its outer position.

In testimony whereof I affix my signature.

MATTINE F. DECKER.
